FLASHLIGHT

Milton S. Dunkelberger, Dayton, Ohio

Application September 28, 1950, Serial No. 12,379

Term of patent 14 years

(Cl. D48—24)

To all whom it may concern:

Be it known that I, Milton S. Dunkelberger, a citizen of the United States, residing at Dayton, State of Ohio, have invented a new, original, and ornamental Design for Flashlight, of which the following is a specification, reference being had to the accompanying drawing, forming a part hereof.

Figure 1 is a side elevational view of a flashlight showing my new design;

Figure 2 is a fragmentary side elevational view taken at right angles to Figure 1 with the lower part of the casing broken away for convenience of illustration;

Figure 3 is an end elevational view; and

Figure 4 is a fragmentary elevational view showing the side opposite Figure 2.

I claim:

The ornamental design for a flashlight, as shown.

MILTON S. DUNKELBERGER.
